By his Attorneys,

George W. Baker,
C. Snowdon.

Inventor

UNITED STATES PATENT OFFICE.

GEORGE W. BAKER, OF COLMESNEIL, TEXAS.

SHEARS.

SPECIFICATION forming part of Letters Patent No. 444,970, dated January 20, 1891.

Application filed September 17, 1890. Serial No. 365,205. (No model.)

To all whom it may concern:

Be it known that I, GEORGE W. BAKER, a citizen of the United States, residing at Colmesneil, in the county of Tyler and State 5 of Texas, have invented new and useful Shears, of which the following is a specification.

My invention relates to improvements in shears which are adapted to be run along the 10 top of the table or other surface, whereby the movable blade is adapted to be operated so that cloth, paper, or other material may be severed.

In the accompanying drawings, Figure 1 is 15 a side view, and Fig. 2 a top view, of my invention.

A is the lower member of a pair of shears, provided with a handle B, said lower member being provided also with a cutting-edge a. 20 Pivoted to the lower member at C near the top thereof is the movable upper member D, provided with a cutting-edge d.

E is a roller journaled near the heel a' of the lower member and provided with an 25 elongated eccentric-pin F on its outer side. Extending rearwardly from the upper member D is a projection G, provided with a suit-

able elongated opening g, in which the pin F is adapted to work.

It will be apparent that in running the 30 shears over a table in vertical position, so that the roller will engage the top of the table, the upper member will be operated by the engagement of the eccentric-pin at the side of the roller with the opening in the rear- 35 wardly-extending projection.

What I claim as new is—

In a pair of shears, the combination, with a lower member provided with a handle, of a roller journaled to said member and provided 40 with an elongated eccentric-pin, an upper member pivoted to said lower member, and a rearwardly-extending projection from said upper member provided with a suitable elongated opening for the engagement of said 45 pin, substantially as and for the purpose set forth.

In testimony that I claim the foregoing as my own I have hereto affixed my signature in presence of two witnesses.

GEORGE W. BAKER.

Witnesses:

W. M. SCOTT,
W. J. BLUVETT.
